MAGNETIC DRUM DATA STORAGE DEVICE OR SIMILAR ARTICLE

Joseph J. Bourdon, Royal Oak, and Merton L. Ripley,
Milford, Mich., assignors to Ex-Cell-O Corporation,
Detroit, Mich.

Filed Apr. 8, 1963, Ser. No. 74,326

Term of patent 14 years

(Cl. D26—5)

FIGURE 1 is a top perspective view of a magnetic drum data storage device or similar article, showing our new design; and

FIGURE 2 is a perspective bottom view thereof.

We claim:

The ornamental design for a magnetic drum data storage device or similar article as shown.
